(57) CLAIM

The ornamental design for a sunvisor, as shown and described.

DESCRIPTION

FIG. 1 is a perspective view of the sunvisor showing my new design, the dashed line illustration of the vehicle interior showing the sunvisor in its environment attached to a rear view mirror is for illustrative purposes only and does not form a part of the present invention;

FIG. 2 is an enlarged front elevational view thereof;

FIG. 3 is an enlarged bottom plan view thereof;

FIG. 4 is an enlarged top plan view thereof;

FIG. 5 is an enlarged rear elevational view thereof; and,
FIG. 6 is an enlarged right side elevational view thereof, the left side elevational view being identical.
